[57] **CLAIM**

The ornamental design for a translucent jogging shirt with harness for carrying a portable electronic device, as shown and described.

DESCRIPTION

FIG. 1 is a perspective view of the translucent jogging shirt with harness for carrying a portable electronic device illustrating my new design;

FIG. 2 is a perspective view of the translucent jogging shirt with harness for carrying a portable electronic device of FIG. 1 shown being worn by a person and having a portable electronic radio attached; the broken lines are for environmental purposes only and form no part of the claimed design;

FIG. 3 is a rear elevational view of the translucent jogging shirt with harness for carrying a portable electronic device shown in FIG. 1;

FIG. 4 is a top plan view of the translucent jogging shirt with harness for carrying a portable electronic device thereof; and,

FIG. 5 is a right side elevational view of the translucent jogging shirt with harness for carrying a portable electronic device thereof, the left side view being the mirror image of that shown; the broken lines are for environmental purposes only and form no part of the claimed design.
